UNITED STATES PATENT OFFICE

125,639

DESIGN FOR A MERCHANTISE DISPLAY RACK

Milton H. Larson, Bronson, Mich., assignor to L. A.
Darling Company, Bronson, Mich., a corporation of Delaware

Application July 8, 1940, Serial No. 93,496

Term of patent 14 years

To all whom it may concern:

Be it known that I, Milton H. Larson, a citizen of the United States and resident of Bronson, in the county of Branch and State of Michigan,
have invented a new, original, and ornamental Design for a Merchandise Display Rack, of which the following is a specification, reference being had to the accompanying drawing, forming a part thereof.

The drawing is a perspective view of a merchandise display rack, showing my new design.

I claim:

The ornamental design for a merchandise display rack, substantially as shown.
